METHOD AND APPARATUS FOR WEEDING THE FLAME PLASMA OF A ROCKET EXHAUST
William W. Balwanz, Alexandria, Va., assignor to the United States of America as represented by the Secretary of the Navy

Filed June 17, 1964, Ser. No. 375,989
5 Claims. (Cl. 60—205)

The invention described herein may be manufactured and used by or for the Government of the United States of America for governmental purposes without the payment of any royalties thereon or therefor.

The present invention relates to a method and apparatus for weeding or reducing the ionizations in hot exhaust gases. More particularly, the invention relates to a plasma weeding method which is capable of minimizing exhaust interference with communication links.

Rocket aircraft in flight relay information by radio to the ground. In this case and also when radar methods are used to track the vehicle, or when it is controlled by radio signals from a ground-based guidance system, there may be considerable interference with the signal due to the electromagnetic properties of hot exhaust gases. The combustion process in rocket motors evolves free electrons, free radicals and other transient species that form flaming trails of highly ionized media. Electromagnetic radiation passes through an un-ionized gas, such as air, without interference. When the gas is partly ionized, however absorption, reflection and refraction of the transmitted radiation results in a considerable loss of signal and therefore decreased reliability in the guidance and tracking systems.

Absorption and phase shift experienced by the electromagnetic radiation depend on the concentration of free electrons formed by thermal ionization of exhaust gases, the electron concentration increasing rapidly with temperature. A typical concentration would be about 10^{10} electrons per cubic centimeter. Electrons are also emitted from hot solid particles of soot or metal in the exhaust, just as they are emitted from the heated cathode of a vacuum tube. If the propellant is fuel rich, afterburning will take place when the exhaust mixes with the surrounding atmosphere, and this too causes further increase in ionization.

It has previously been proposed to include certain materials in the fuel-oxidant mixtures to improve the combustion process and modify the composition of the exhaust gases. Extensive experimentation has proved that it is very difficult to alter temperature or composition of the propellant gases without incurring a substantial reduction in performance. Other methods have been advanced in the past for removing electrical charges from hot exhaust gases by applying electrical collection or deflection probes, but these devices were wholly ineffective for weeding high electron densities from a flame plasma.

The term "flame plasma" refers to the limited degree of ionization which exists in hot exhaust gases in which the gaseous state contains approximately equal densities of charged carriers of opposite polarities.

The present invention concerns an effective weeding method for reducing the ionization of a rocket exhaust to a level where it can not interfere with radar and radio signals. More specifically, the present method reduces the electron density in the plasma by means of a weeder substance which is introduced directly into the exhaust during the flight of the rocket craft. The weeder method described herein differs from previous methods dealing with electrical charge which were directed primarily to the propellant properties during combustion. The weeder in accordance with the invention is utilized in such a manner

that it does not interfere with the propulsion process, but is directed entirely on the products of combustion as they escape from the rocket throat.

An object of the present invention is to provide a method which can be used on rocket-propelled craft or jet engines to suppress the exhaust flame.

Another object is to provide fluid injection means on a rocket for rapid mingling of a weeder substance with the combustion products from the engine.

10 A further object is to provide a method which minimizes exhaust interference with radio and with radar probes.

15 Another object is to provide a fluid discharge element for introducing a weeder substance near the exhaust nozzle of a rocket, said substance being effective in reducing free electron charge near said nozzle.

20 Other objects and advantages will be readily apparent from consideration of the following detailed description taken in connection with the accompanying drawing in which:

FIG. 1 illustrates schematically a portion of a rocket engine which includes a plasma-weeding injector in accordance with the present invention, and

25 FIGS. 2 and 3 graphically illustrate the improvement in signal transmittance by introducing a weeder substance into the exhaust flame.

30 In accordance with the invention, electron reduction is achieved in a rocket exhaust by injecting one or more substances into the exhaust flame at a suitable flow rate. Substances which may be utilized for this purpose are the Freon gases, water, water vapor and potassium sulfate.

35 Any additive which prevents the addition of energy to the plasma tends to reduce the electron concentration by forming a radiative and dispersive medium capable of dissipating the energy. However, for the purposes of the present invention, the compounds disclosed are capable of forming ionizable components with high bonding strength for free electrons. Compounds with a high 40 electron attachment coefficient can help reduce the electron density by producing negative ions which interfere negligibly with electromagnetic signals because of their increased mass. Weeder components are at a much lower temperature than the flaming gases thus tending to reduce the temperature of the exhaust by dilution. When the weeder is added as a liquid, the cooling effect of vaporization also combines with the cooling effect by dilution to provide a further reduction in temperature. Thus, any weeder compound if injected in sufficient quantity may 45 reduce the exhaust ionization. However, the basis on which plasma weeders have been selected depends on their ability to inhibit and retard chemical action in the flame and on their electron affinity for removing free electrons. These mechanisms provide substances of practical 50 utility at nominal dispensing rates for airflight applications. Other substances containing elements of high attachment coefficients, for example the halogens, are not necessarily effective weeders for the most part in high temperature exhausts because they may induce 55 chemical reaction and add heat to the system causing higher thermal ionizations.

60 The weeder substances disclosed herein are preferably used at flow rates not exceeding about 20% the flow rates of the propellant mixtures. A substantial decrease in 65 radiation losses is noted when the present weeder compounds are used in amounts of about 4-20% based on the propellant rate of consumption. Radiation losses by absorption, reflection, etc. which do not exceed about 2% of the incident beam are considered negligible insofar as interference with radar or radio receivers is concerned. Plasma weeders add to the weight problem of a rocket

and therefore should be utilized preferably at flow rates of about 5% based on the propellant rate.

The Freon gases are particularly effective weeders, except in high hydrogen-content exhausts with temperatures above 2500° K.; the gaseous release of these compounds cause a rapid reduction in plasma temperature. In addition, Freon compounds are capable of inhibiting the flame by reducing the flame combustion rate. Compounds which have been found to be particularly useful as weeders in accordance with the present invention are the dichlorodifluoromethane, CCl_2F_2 , the dibromodifluoromethane, CBr_2F_2 , and the bromotrifluoromethane, $CBrF_3$ or mixtures of these compounds.

Water is a most effective weeder and may be used as a liquid or discharged as steam vapor. The water molecule has a high cooling action due to its high specific heat; its high electron affinity results in H_2O^- and ion $OH^- + H$ formation. The reactions of the water molecule with free electrons may be indicated as follows:

Having a high ionization potential, the water molecule does not form ion components, nor is it chemically reactive with most exhaust products.

The effectiveness of potassium sulfate as a weeder component may be explained in terms of its elements which have a relatively low heat of reaction and tend to take heat away from the plasma. A potassium sulfate solution, may combine the mechanisms involved in water and in the sulfate effectively to suppress free electron formation at even lower rates of flow. Small quantities of the solid material may be included in the rocket engine and dispensed by melting or ablating during exposure to the exhaust jet.

Referring now to FIG. 1, a schematic diagram of a rocket engine 11 of conventional configuration shows a portion of a combustion chamber 12, the aft portion thereof converging to a narrow throat 13. The nozzle 14, through which the internally developed gases can escape, is shown as a straight expansion cone. A supply tank 15 is located in the fore region of the engine away from the heat of the combustion chamber. The tank which stores the weeder substance is connected by a pipeline 16 to an injection manifold ring 17 located at or near the throat region. The manifold ring surrounds the engine externally to prevent interference with the cross section at the throat; said ring conveys the weeder fluid to various points in the throat or nozzle regions through a plurality of outlets or ducts 18 that pass through the engine wall. Force-operated equipment such as a variable pump 22 that pumps the fluid through the pipeline in which the solution is controlled by a suitable pressure activated control valve 23 through which the pump forces the fluid into the nozzle region as a fine spray; the opening in said outlets control the amount of fluid injected into the nozzle region. The rocket exhaust flame 19 sweeps the fluid into the body of the flame. In view of the force of the exhaust, the fluid should be introduced into the body of the flame to prevent surface sweep. Alternately, the weeder may be introduced in the expansion cone, for example, from an injector ring surrounding the cone region at point 21, in a further effort to improve the penetration of the weeder into the flame region.

In the operation of a rocket-powered craft, the propellant consisting of a fuel and a fuel oxidizer when brought together in the combustion chamber combine exothermally in a temperature range from 2000 to 4000° K. and at chamber pressures of about 300 pounds per square inch to provide propulsion of the craft. After sufficient thrust has been created to push the craft off the ground, it rises above the earth and its propellant burns and produces flaming exhaust gases. Signal loss due to the flame is lessened appreciably by injecting a weeder in accordance with the present invention. The weeder for example may

be liquid dibromodifluoromethane or water sprayed into the exhaust stream. The weeder is pumped at a constant flow rate and injected as a fine spray from equally spaced outlets. The force of spray may induce shock waves, as demonstrated with water vapor in the example below. A dense liquid stream under force may induce shocks of such proportion that more electrons will be created than the weeder is able to remove.

Tests conducted with electromagnetic probes provide a measure of the electron reduction which may be achieved by means of weeder action. FIGS. 2 and 3 demonstrate graphically the loss of electromagnetic energy incurred from ionizations in the exhaust flame of a 1500-pound thrust rocket motor, and the improvement that can be obtained by means of weeder injections. The graphs also indicate the dependence of electron reductions on the concentration of the weeder substance. Electromagnetic energy was provided by square wave modulated klystrons to transmitting antennas. The energy received was rectified and the video output amplified and displayed on a cathode ray tube for photographic recordings. Changes in the amplitude of this recorded pulse gave a measure of the loss of energy due to the conditions of the exhaust flame. FIG. 2 demonstrates the energy loss in decibels before and during the injection of water to the exhaust flame. Prior to the weeder injection, the energy loss was about 37% of the incident wave beam. When the water was turned ON at a rate of 1.7 pounds per minute which was approximately 17% of the propellant flow rate decreased the energy loss to less than 0.2%. When the water spray was turned OFF, the energy loss immediately increased to the previous level. The horizontal axis on the graph is the time parameter. FIG. 3 similarly demonstrates the decrease in energy loss resulting from the injection of steam at a lower rate of flow. The steam was injected at about 0.5 pound per minute or approximately 5% of the propellant rate of flow. The improvement with steam injection was less than in the previous test due to the lower flow rate and to shock ionization which created a stepwise increase in absorption loss.

It will be apparent that the selection of weeding material and the rate at which it is introduced to an exhaust stream to obtain optimum transmittance of electromagnetic signal will vary with rocket design and with propellant composition. In practise, therefore, the weeder selected and the amount injected into a flame must be based on the flame plasma existing in a particular rocket exhaust.

Various modifications are contemplated and may obviously be resorted to by those skilled in the art without departing from the spirit and scope of the invention. It is therefore to be understood that within the scope of the appended claims the invention may be practised otherwise than as specifically described.

What is claimed is:

1. A method for weeding the flame plasma of a rocket exhaust resulting from the combination of propellants in a rocket engine which comprises:

injecting a substance into the exhaust flame of a rocket engine within the exhaust nozzle thereof, said substance being selected from the group of substances consisting of CBr_2F_2 , $CBrF_3$, and K_2SO_4 and being injected into the flame at a flow rate in the range of from about 4 to about 20 percent based on the flow rate of the propellant.

2. A method for weeding the flame plasma of a rocket exhaust resulting from the combination of propellants in a rocket engine which comprises:

injecting a substance into the exhaust flame of a rocket engine within the exhaust nozzle thereof, said substance consisting essentially of CBr_2F_2 and being injected into the flame at a flow rate in the range of from about 4 to about 20 percent based on the flow rate of the propellant.

3. A method for weeding the flame plasma of a rocket

exhaust resulting from the combination of propellants in a rocket engine which comprises:

injecting a substance into the exhaust flame of a rocket engine within the exhaust nozzle thereof,

said substance consisting essentially of $CBrF_3$ and being injected into the flame at a flow rate in the range of from about 4 to about 20 percent based on the flow rate of the propellant.

4. A method for weeding the flame plasma of a rocket exhaust resulting from the combination of propellants in a rocket engine which comprises:

injecting a substance into the exhaust flame of a rocket engine within the exhaust nozzle thereof,

said substance consisting essentially of K_2SO_4 and being injected into the flame at a flow rate in the range of from about 4 to 20 percent based on the flow rate of the propellant.

5

5. A method for weeding the flame plasma of a rocket exhaust resulting from the combination of propellants in a rocket engine in accordance with claim 4 in which said substance is injected as an aqueous solution.
